(57) **CLAIM**

The ornamental design for an oyster opener, as shown and described.

DESCRIPTION

FIG. 1 is a front perspective view of an oyster opener, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is a front perspective view of the oyster opener shown in an open position; and,

FIG. 10 is an enlarged detail view of area 10 in FIG. 2. The dash-dot-dash broken lines represent the boundaries of the enlarged portions and form no part of the claimed design.
